W. S. Sprague

UNITED STATES PATENT OFFICE.

JENS A. WANG, OF ALPENA, MICHIGAN.

PANTOGRAPH.

SPECIFICATION forming part of Letters Patent No. 350,027, dated September 28, 1886.

Application filed April 8, 1886. Serial No. 198,198. (No model.)

To all whom it may concern:

Be it known that I, JENS A. WANG, of Alpena, in the county of Alpena and State of Michigan, have invented new and useful Improvements in Pantographs; and I do hereby declare that the following is a full, clear, and exact description thereof, reference being had to the accompanying drawings, which form a part of this specification.

10 This invention relates to certain new and useful improvements in pantographs; and the invention consists in the peculiar construction, arrangement, and combinations of the various parts, all as more fully hereinafter set forth.

Figure 1 is a perspective of my improved pantograph. Fig. 2 is a section through one of the joints.

In the accompanying drawings, which form a part of this specification, A B C represent three rules pivotally secured together, as at *a*, and in this construction these points are never changed in adjusting the device to produce drawings of different sizes.

25 D is an adjustable rule or bar, which, together with the rules A and C, are provided with a series of holes, consecutively numbered, by means of which and suitable thumb-screws or pins they may be pivotally secured together. As the rule or bar D has to be pivotally secured at two points, it necessarily follows that it should be numbered from both ends with numbers corresponding to those upon the rules A C. One end of the bars D and B are slotted, as shown, cut through a hole, *b*, at right angles to the slot, such holes being designed to receive the point and pencil and to be held therein by the thumb-screws *c*, as shown.

30 E is a clamp designed to be secured to the edge of the drawing-table by the screw F. To

the upper end of this clamp is pivotally secured a block, G, to which the end of the rule A is pivotally secured by means of the pin or screw *d*. The screws H, which pivotally secure the rules together, are provided with a cup-shaped washer, I, which forms a bearing for the head of the screws, and upon which they turn without unscrewing when in use.

45 In practice, fasten the machine securely at 50 left side of table, about at the middle, by means of the clamp E. If drawing is wanted larger than original, place pencil in arm B, and pointer in arm D; if smaller, reverse. If a drawing near the original in size is wanted, 55 let A D and A C cross each other at Fig. 1. If a very large or very small size is wanted, let A D and A C cross at a higher figure, care being taken always to cross at same figure upon each rule, as 1 1 1 1, 9 9 9 9, 18 18 18 18 18. 60 Fasten pencil securely with thumb-screw one and one-half inch from point, and fasten pointer so that it touches paper very light when pencil is pressed down on paper. When drawing, take hold of pencil with right hand 55 and let pointer follow lines in original.

What I claim as my invention is—

In a pantograph, the combination of the rules A C, the rule B, pivoted on permanent pivots *a* to one end of said rules and provided 70 with pencil-point, the rule D, adjustable on the rules A C parallel with the rule B and carrying pointer, the block G, pivotally secured to the end of the rule A, and the clamp E, pivoted to the block G and provided with 75 screw F, substantially as and for the purpose specified.

JENS A. WANG.
